UNITED STATES PATENT OFFICE.

HORATIO O. PERRY, OF BUFFALO, NEW YORK, ASSIGNOR TO HIMSELF AND SIDNEY SHEPPARD, OF SAME PLACE.

MEANS FOR SECURING THE ARMS TO THE HUBS OF PROPELLERS.

Specification forming part of Letters Patent No. 22,266, dated December 7, 1858; Reissued April 28, 1863, No. 1,467.

To all whom it may concern:

Be it known that I, HORATIO O. PERRY, of Buffalo, in the county of Erie and State of New York, have invented certain new and 5 Improved Means of Securing the Arms to the Hubs in Screw-Propellers; and I do hereby declare that the following is a full, clear, and exact description of the same, reference being had to the accompanying drawings, and to the letters marked thereon, in 10 which—

Figure 1 is a plan view. Fig. 2 is an end elevation of my screw or propelling wheel complete. Fig. 3 is a section of a portion on 15 line S S in Fig. 2. Fig. 4 is a view showing the arrangement of the keys alone. Fig. 5 is a view showing the arrangement of the keys when 5 arms and keys are employed. Fig. 6 is a similar view showing the ar- 20 rangement when but 3 arms are used.

Similar letters of reference refer to like parts in all the drawings.

The nature of my invention consists in fitting the arms into conical sockets in the 25 hubs, and in confining the parts together by keys so arranged that the small end of the second key extends across the head of the first, the small end of the third extends across the head of the second, and the small 30 end of the fourth across the head of the third, so that none of the other keys can by any chance be displaced until the fourth has been first removed.

To enable others skilled in the art to make 35 and use my invention I will proceed to describe its construction and operation by the aid of the drawings.

A is the shaft of the propeller.

B is the hub or central boss constructed as 40 represented with four stout bosses or short branches B' in each of which is a tapering socket to receive a corresponding end of one of the arms or blades C C C C. The keys D' D² D³ D⁴ are tapered very slightly and 45 are very strongly fitted in the transverse seats represented, so that each key serves to confine its respective arm into its socket, while each with the exception of the first also serves to confine a neighboring key.

50 In constructing my improved screw or propelling wheel, I first take care that the parts are properly cast and truly finished and the central casting B firmly secured upon A. I then insert the conical extrem-

ity of one of the arms C into one of the corresponding sockets in B, and drive the key D', which must be too short to stand in the path of either of the other keys. I then insert the next arm and drive the key D² taking care to drive each key very firmly to 60 its proper place. This key D² must be of such proportions that when fairly driven its widest end is out of the path or "wake" of the next key D³, while its narrowest end extends partly across the end of, and confines, 65 D'. I then insert the next arm and drive D³ in the same manner, so that D³ confines D². I then insert the last arm and drive D⁴, after which I confine the last key D⁴ by any ordinary means. When it is desired to remove all or any one of the arms from my wheel, the process above described or a portion thereof is reversed.

The object of my invention is to cheapen 75 the construction, increase the strength and diminish the volume, and also to diminish the liability to derangement, of the parts of a propeller. The means by which blades have been heretofore connected and disconnected are objectionable. When the blades 80 are riveted to the arms it involves great labor to separate them and still more labor and skill properly to connect again. When bolts and nuts or any of the more complicated devices are used, these difficulties are 85 but little diminished while new and serious ones are involved. The various expedients for feathering the blades are objectionable on account of the bulk of the mechanism at the center as also from the liability of the 90 parts to become deranged.

I am not aware that conical sockets in the hub, and corresponding conical ends on the arms, with keys arranged in the manner 95 herein described and represented have ever been before employed. I have found by experience that the connection of arms to the hub in my invention is very strong and im- 100 movable and that a separation of the parts is effected with less labor and the substitu- 100 tion of other arms previously prepared is performed in less time than by any other invention for the purpose.

My invention may be applied without diffi- 105 culty where any number of arms greater than two are employed. Fig. 5 is an example showing the arrangement of the keys where five arms are employed and Fig. 6

shows the arrangement where only three arms are used.

I do not confine myself to any precise degree of taper to the conical ends of my 5 arms, nor do I confine myself to the employment of four arms. But

Having now fully described my improvement what I claim as my invention is—

The employment of the conical ends C'

confined in the corresponding sockets in B' 10 by the keys D', D², D³, etc., substantially in the manner and for the purposes above set forth.

HORATIO O. PERRY.
